UNITED STATES PATENT OFFICE.

EMIL WILHELM STROHN, OF BUFFALO, NEW YORK.

VACUUM DRYING APPARATUS.

No. 921,307.

Specification of Letters Patent.

Patented May 11, 1909.

Application filed November 23, 1908. Serial No. 464,173.

To all whom it may concern:

Be it known that I, EMIL WILHELM STROHN, a subject of the German Emperor, residing at Buffalo, in the county of Erie and 5 State of New York, have invented a new and useful Improvement in Vacuum Drying Apparatus, of which the following is a specification.

This invention relates to an apparatus for 10 removing moisture and volatile ingredients under a vacuum from fabrics, belts, cables, cords and other materials which are manufactured in webs or considerable lengths and are wound upon drums or reels.

15 The apparatus comprises, briefly stated, an air-tight casing which communicates with an exhaust mechanism and is otherwise closed, heating chambers arranged in said casing at suitable distances apart so that the 20 web of material can travel back and forth between these chambers, propelling rolls which are arranged within the casing and draw the material through the apparatus, and a drum or reel upon which the finished 25 material is wound and which is also arranged within the casing.

In the accompanying drawings, consisting 30 of four sheets: Figure 1 is a side elevation of my improved drying apparatus. Fig. 2 is a vertical longitudinal section of the same, in line 2—2, Fig. 4. Fig. 3 is a vertical transverse section in line 3—3, Fig. 2. Fig. 4 is a top plan view. Fig. 5 is a fragmentary longitudinal section showing a modified construction of the front portion of the apparatus. Fig. 6 is a fragmentary longitudinal section of the rear portion of the apparatus, illustrating a modified construction thereof. Fig. 7 is a fragmentary horizontal section in 40 line 7—7, Fig. 6.

Like reference characters refer to like parts in the several figures.

Referring to Figs. 1—4, A represents the body of the air-tight casing provided at its 45 front end with a door 20 for the introduction of the web, fabric or other material to be treated and having at the opposite or rear end a door 21 for the removal of the treated roll of material. These doors are balanced 50 by counterweights 22, 23, so that they can be conveniently applied and removed. The body of the casing is provided with a raised top portion or dome 24 which is provided with an exit opening 25 by which the apparatus 55 communicates with a suitable vacuum

or exhaust and condensing apparatus. This dome is provided with a removable cover 26 for giving access to the interior.

B represents the heating chambers or sections which are arranged vertically in the 60 middle portion of the apparatus and which extend into the dome thereof. These chambers are preferably flat-sided boxes arranged transversely in the apparatus and receive steam from a manifold head 27 through individual pipes 28 and discharge the condensed water through individual pipes 29 and a manifold head 30.

31 represents guide rolls, arranged in the dome above the heating sections, and 32 70 represents guide rolls arranged below the sections in such manner that the web C of material is directed upwardly on one side of each section and downwardly on the opposite side.

33 represents the drum or reel which contains the web to be treated and is arranged within the front portion of the casing. The web passes from this reel downwardly to the first lower guide roll 32, thence upwardly 80 and around the first upper roll 31, thence downwardly to the second lower roll 32, and so on until it has passed around the last lower roll 32 from which the web passes to a pair of propelling rolls 34. These propelling rolls 85 are driven by any suitable mechanism, for instance, as shown, by a train of gear wheels 35, 36, 37 and 38, the two rolls 34 being connected by gear wheels 39. Pressure is applied to these rolls by springs 40 or other 90 means for gripping the web, unwinding the same from the reel 33, and propelling the same through the apparatus. A band brake 41, 42 is preferably applied to this reel for controlling its unwinding movement. 95

43 represents the receiving reel upon which the treated web is wound and which is arranged within the rear portion of the casing. This reel receives the web C from the propelling rolls 34 and may be driven by any suitable mechanism, for instance, as shown, by a belt 44 running around pulleys 45, 46.

When this apparatus is used for drying material which has been impregnated with a sticky substance, for instance, an insulating 105 composition, it is desirable to keep the sticky layers or convolutions on the receiving reel separate, and for that purpose a web D of dry material is wound upon the receiving reel simultaneously with the web of impreg- 110

nated material. The web D is unwound from an auxiliary reel 47 which is preferably provided with a band brake 48, 49.

In the operation of this apparatus the reel 5 containing the web to be treated is introduced into the front portion of the apparatus and the web is passed around the series of guide rollers and between the propelling rolls and attached with its end to the receiving reel in the rear portion of the apparatus. The casing is then closed and exhausted and the web is slowly passed from the unwinding reel to the receiving reel. During its passage from one reel to the other the material is exposed to the heat given off by the heating chambers, while under a more or less perfect vacuum, whereby moisture or volatile matter contained in the web of material is thoroughly removed. This apparatus may be 10 used for drying fabrics before impregnating them with insulating or other liquids or for drying the fabric after it has been so impregnated. In the latter case the volatile ingredients of the insulating composition are 15 removed and recovered during the drying operation. The dome containing the upper portions of the heating chambers concentrates the heat upon the upper portions of the convolutions of the web and causes a 20 thorough heating of the web at the point where the exhaust is most directly applied. When the web to be treated is folded, as represented in Fig. 5, instead of being wound upon a drum or reel, the front portion of the 25 casing is provided with a pair of guide rolls 50, between which the web passes in being unfolded and in passing to the first lower guide roll. When the apparatus is used for 30 treating material which is not sticky and 35 does not require the employment of a separating web D, as in drying material preparatory to impregnating the same, the rear portion of the apparatus can be reduced in height, as represented in Fig. 6. The sides 40 of the casing are preferably provided with 45 transparent plates 51, 52, for illuminating the interior of the apparatus and observing its operation.

I claim as my invention:

50 1. The combination with a hermetically-closed casing adapted to be exhausted, of heating chambers arranged within said casing and separated by intervening spaces, guide rolls arranged at opposite ends of said 55 heating chambers, propelling rolls arranged

in rear of said heating chambers and adapted to draw the web of material to be treated around said guide rolls and past said heating chambers, and a receiving reel arranged within said casing in rear of said propelling 60 rolls, substantially as set forth.

2. The combination with a hermetically-closed casing adapted to be exhausted, of heating chambers arranged within said casing and separated by intervening spaces, 65 guide rolls arranged at opposite ends of said heating chambers, propelling rolls arranged in rear of said heating chambers and adapted to draw the web of material to be treated around said guide rolls and past said heating 70 chambers, a receiving reel arranged within said casing in rear of said propelling rolls, and an auxiliary reel arranged in the rear portion of said casing for supplying a separating web to the receiving reel, substantially 75 as set forth.

3. The combination with a hermetically-closed casing adapted to be exhausted, a reel arranged in the front portion of said casing and containing the web of material to be 80 treated, of heating chambers arranged within said casing and separated by intervening spaces, guide rolls arranged at opposite ends of said heating chambers, propelling rolls arranged in rear of said heating chambers 85 and adapted to draw the web of material to be treated around said guide rolls and past said heating chambers, and a receiving reel arranged within said casing in rear of said propelling rolls, substantially 90 as set forth.

4. The combination with a hermetically-closed casing provided with a raised dome between its front and rear portions and adapted to be exhausted, of upright heating chambers having their upper portions arranged within said dome, guide rolls arranged at opposite ends of said heating chambers, propelling rolls arranged in rear of said heating chambers and adapted to draw the web of material to be treated around said 95 guide rolls and past said heating chambers, and a receiving reel arranged within said casing in rear of said propelling rolls, substantially as set forth.

Witness my hand in the presence of two 105 subscribing witnesses.

EMIL WILHELM STROHN.
